United States Patent Office

Des. 198,413
Patented June 9, 1964

198,413

HUMIDIFIER

Lawrence E. Wolske, Benton Harbor, Mich., assignor to
Whirlpool Corporation, a corporation of Delaware

Filed July 3, 1963, Ser. No. 75,664

Term of patent 14 years

(Cl. D62—4)

FIG. 1

FIG. 2

FIG. 3

FIGURE 1 is a front elevational view of a humidifier showing my new design.

FIGURE 2 is a plan view thereof.

FIGURE 3 is a perspective view thereof.

The portions not shown are substantially the same as those shown. The humidifier has four equally spaced legs including casters. All of the legs and casters are substantially the same as those shown.

I claim:

The ornamental design for a humidifier, substantially as shown and described.
